RIVET DRIVING MACHINE,
APPLICATION FILED AUG. 7, 1905.

2 SHEETS—SHEET 2.

UNITED STATES PATENT OFFICE.

WILLIAM P. ALLISON, SR., OF KENNEBUNK, MAINE, ASSIGNOR TO THE LEATHEROID MANUFACTURING COMPANY, OF KENNEBUNK, MAINE, A CORPORATION OF MAINE.

RIVET-DRIVING MACHINE.

No. 839,088.

Specification of Letters Patent.

Patented Dec. 25, 1906.

Application filed August 7, 1905. Serial No. 272,984.

To all whom it may concern:

Be it known that I, WILLIAM P. ALLISON, Sr., of Kennebunk, in the county of York and State of Maine, have invented certain new and useful Improvements in Rivet-Driving Machines, of which the following is a specification.

My invention relates to machines for inserting rivets in sheet material, such as fiber board, and has for its object the provision of a machine whereby a large number of rivets may be simultaneously forced through the lap in a sheet or sheets of material to the position they are to occupy in the finished work, and thus be ready to be headed, or in the case of pronged rivets or hollow rivets they may be clenched as they are set in the material.

My machine consists of an upright stand-frame carrying two horizontally-projecting arms between which the lap of the sheets of material to be united is clamped, and in one of said arms is inserted a slide carrying a row of rivets which are by the action of suitable mechanism forced through the material to their proper places, each rivet acting as its own punch, all as set forth in the detailed description following.

In the drawings accompanying this specification and forming a part thereof, Figure 1 is a perspective of the machine; Fig. 2, an end view; Fig. 3, a longitudinal vertical section; Fig. 4, a cross-section; Figs. 5 and 6, enlarged details; Fig. 7, a view of the slide carrying the rivets; Fig. 8, an enlarged view, and Fig. 9 a perspective of a portion of the same; Fig. 10, an end view of the horizontal arms, partly in section.

The working parts of the machine are supported on a frame consisting of a base 1, carrying the heavy webbed upright 2 at one end and at the other an upright pillar 3. Extending from the upright 2 to the pillar 3 and supported thereon is the horizontal hollow beam 4, and above it is the arm 5, projecting from and supported by the upright 2.

The outer end of arm 5 is held to the beam 4, when desired, by a swinging lever 6, which is jointed to the end of beam 4, (see Fig. 10) and may be swung upward so as to pass between two lugs 17 on the end of the upper arm 5. A pivoted handle 30 embraces the end of this lever and presses upon

the top of the lugs 17, and as its rounded end is made slightly cam-shaped it grips the lugs 55 strongly when moved to the horizontal position, (shown in dotted lines in Fig. 3) and thus the arm 5 is held from springing away from the beam 4 when pressure is exerted in the operation of the machine. 60

The upright member 2 of the frame carries two shafts 7 and 10 in bracket-boxes extending therefrom. The upper shaft 7 carries a gear 8 and a cam-wheel 9. The lower shaft 10 carries a pinion 15 meshing into the gear 65 8 and a pulley 11 loose on the shaft, but which is connected to a clutch 12, so that the shafts may be started or stopped by the engagement or disengagement of the clutch with the pulley to which the driving power is attached. 70 This clutch is operated through the horizontal rod 13, running the length of the machine and hung in bearings in the upright 2 and pillar 3. At the end of this rod nearest the clutch and directly below it is attached 75 an arm 14, which operates the clutch when the rod is turned on its axis, as it may be by the lever-handle 16 near its opposite end.

The beam 4 (shown in cross-section in Fig. 4) has a rectangular recess extending its 80 whole length, in the bottom of which lies a bar 18, which is longitudinally movable for a short distance and is operated by the bell-crank lever 20, which is connected by a vertical rod 21 with another bell-crank lever 22 85 near the base of the machine and which is operated from the treadle and lever 23, connected by the horizontal rod 24. (See Fig. 1.) When the treadle 23 is depressed, it moves the horizontal rod 24 to the right and 90 the vertical rod 21 downward, and this draws the bar 18 toward the left.

In Fig. 1 will be seen a pawl 25 just above the treadle, which enters a ratchet on the side of the pillar 3, so as to hold the treadle 95 and its connections in the position in which they are placed by the depression of the treadle.

In Fig. 3 will be noticed a series of angular notches or inclined planes in the upper edge 100 of the bar 18. These fit corresponding elevations and depressions in the upper bar 19, which is movable vertically, but not horizontally, so that when the lower bar is drawn to the left as described the upper one is raised 105 by the inclined projections and notches.

When the bar 18 is drawn to the left, the holes in it register with the holes in 19.

Figs. 5 and 6 show enlarged sections of the bars 18 and 19, the former showing small an-
5 vils *a a*, with an upper contour adapting them to turn the points of split or pronged rivets when pressed upon them. The latter sec-
10 tion, Fig. 6, shows no anvils, but circular holes *c c*, which act as dies to allow the flat-
15 ended rivets shown above them to act as punches to carry a piece of material down through them. In the case of pronged rivets they are clenched, but solid rivets are punched through the material and headed by

15 a subsequent operation.

Coming now to the upper beam 5, as shown in Figs. 3 and 4, it contains a vertically-movable bar 26 and a horizontally-movable one 27. This latter is operated by the cam-
20 wheel 9, to which it is connected by the rod 28 and open frame 29, a portion of which in-
25 closes the cam-wheel 9. The rod 28 is threaded, and nuts *d d* allow of adjustment. Lugs 31 are pivoted to the bar 27 in pairs, each pair having a common pivot at one end and the other end of each pivoted one to the bar 26 the other to the upper portion of the arm 5, so as to form knuckle-joints, and as the bar 28 is drawn to the left by the cam 9
30 the bar 26 is depressed. This bar 26 carries a series of punches *p p*, that register with the anvils or holes in bar 19 in the lower beam 4.

Figs. 7, 8, and 9 show a long slender trough, of steel, containing a row of dies *x* made in
35 halves, which are held in place by springs *z*, riveted to each and to the sides of the trough. These dies are each to hold a rivet supported by its head, and when so loaded the strip containing the dies and rivets is slipped into
40 the arm 5 and, supported by lugs 32, is so placed that the rivets are each directly under one of the punches in the bar 26 and over an anvil or hole in bar 19.

In Fig. 10 is shown in section a sheet of
45 material 33, bent into a cylindrical form with the edges lapped and a rivet passed through the lap. In operating the machine on a cy-
50 lindrical can, as shown in Fig. 10, the edges of the material to be united are lapped and placed around the arm 5, with the lap directly below it. The bar 6 is thrown up, locking the arm 5 to the beam 4. Then the treadle 23 is depressed, thereby drawing the bar 18 to the left, and thus raising the anvil-bar 19,
55 so as to clamp the material to be operated on closely between the anvil-bar 19 and the sup-
60 ports 32 of the slide, Fig. 7, carrying the rivets. The lever-handle 16 is then lifted, thereby operating the clutch 12, and the revolu-
65 tion of the pulley is communicated to the shaft 10 with its pinion, and thereby upper shaft 7 and its cam are revolved, drawing the bar 27 to the left and forcing down the punch-
65 bar 26 and driving the rivets in the slide

through the stock. The halves of the dies *x x* separate when the punch forces the rivets down, so as to allow their heads to pass through.

I claim—

1. In a machine of the character described, the combination of a supporting-frame includ-
70 ing two parallel beams, a laterally-movable bar parallel to and supported by one of said beams, a series of projecting studs or drivers carried by said bar, and means for giving said bar a reciprocating motion at right angles to its axis, a series of rivet-holders reg-
75 istering with said drivers, said rivet-holders having tapering apertures the larger diam-
80 eters of which are at least as large as the heads of the rivets to be suspended therein and each composed of two parts which join in the plane of the axis of the said aperture, independent springs united to each of said parts and normally holding them in contact, and a removable frame inclosing the series of holders and to which said springs are also joined, thus uniting the said holders in a series which when in place in the machine 85 keeps them in register with the said drivers and which may be removed for convenience of filling with rivets, all arranged and to operate as herein set forth.

2. In a machine of the character described, the combination of a series of drivers, means for moving them simultaneously in the direc-
90 tion of their axes, a series of rivet-holders registering with said drivers, said rivet-
95 holders having tapering apertures the larger 100 diameters of which are at least as large as the heads of the rivets to be suspended therein and each composed of two parts which join in the plane of the axis of the said aperture, independent springs united to each of 105 said parts and normally holding them in contact, and a removable frame inclosing the series of holders and to which said springs are also joined, thus uniting the said holders in a series, which, when in place in the ma-
110 chine, keeps them in register with the said drivers, and which may be removed for convenience of filling with rivets; all arranged and to operate as herein set forth.

3. In a machine of the character described, a removable frame, a series of rivet-holders mounted thereon having tapering apertures, the larger diameters of which are at least as large as the head of the rivet to be suspended therein and each composed of two parts 115 which join in the plane of the axis of the said aperture, independent springs united to each of said parts and normally holding them in contact, and also joined to said frame, thus uniting the said holders in a series, which, when in place in the machine, keeps them in register with the said drivers, and which may be removed for convenience of filling 120 with rivets, substantially as shown and de-
125 scribed.

4. In a machine of the character described, the combination of a supporting-frame including two parallel beams, a laterally-movable bar parallel to and supported by one of said beams, a series of projecting studs or drivers carried by said bar and means for giving said bar a reciprocating motion at right angles to its axis, a series of rivet-holders registering with said drivers, said rivet-holders having tapering apertures the larger diameters of which are at least as large as the heads of the rivets to be suspended therein, and each composed of two parts which join in the plane of the axis of the said apertures, independent springs united to each of said parts and normally holding them in contact, and a removable frame inclosing the series of holders and to which said springs are also joined, thus uniting the said holders in a series, which, when in place in the machine, keeps them in register with the said drivers, and a series of anvils or dies mounted upon a bar supported upon the other of said beams, so as to register with said drivers and dies, and mechanism adapted to move said last-mentioned bar toward the said rivet-holders, substantially as set forth.

5. In a machine of the character described,

the combination of two laterally-movable parallel bars, a series of rivet-drivers mounted upon one of said bars, a series of anvils or dies mounted upon the other of said bars so as to register with said drivers, mechanism adapted to move each of said bars independently toward or from the other, and a removable bar supported between said bars and carrying a series of rivet-holders, substantially as shown and described.

6. In a machine of the character described, the combination of a series of drivers adapted to be moved simultaneously in the direction of their axes, and a series of divided rivet-holders, registering with the said drivers and held in normal position by springs which may yield so as to allow the parts of the holders to separate, and rivets contained therein to pass through and out of the same, and a series of anvils or dies registering with said drivers and holders and adapted to be moved simultaneously toward the same, substantially as shown and described.

In testimony whereof I have affixed my signature in presence of two witnesses.
